UNITED STATES PATENT OFFICE.

WALTER H. HOLLSTEIN, OF LAKewood, OHIO.

DEVICE FOR INDICATING THE HORSE-POWER OF AN ENGINE.

1,159,769.

Specification of Letters Patent.

Patented Nov. 9, 1915.

Application filed January 30, 1913. Serial No. 745,091.

To all whom it may concern:

Be it known that I, WALTER H. HOLLSTEIN, a citizen of the United States, residing at Lakewood, in the county of Cuyahoga and State of Ohio, have invented a new and useful Improvement in Devices for Indicating the Horse-Power of an Engine, of which the following is a specification, the principle of the invention being herein explained and the best mode in which I have contemplated applying that principle, so as to distinguish it from other inventions.

The title given my invention sufficiently explains its general character. For the exemplifying purpose in hand it is shown to involve electricity and associated with a portion of a reciprocating type of steam engine.

The primal object of my invention is to effect an instantaneous result.

A further object is the provision of means whereby a direct, continuous and simplified tabulation of successive results is made possible.

Still another object is the origination of a combination of parts which will be simple and economical of manufacture.

In so far as I am conversant with this particular art, devices similar in purpose to mine have heretofore without exception necessitated a laborious log sheet computation. Such computations were based on the readings from charts of various comparative scales which were adapted to receive the recordation of curves. Such charts were moreover frequently upon distinct cards two, four or six according to the number of movements demanding at regular intervals skilled replacing and valued time consumption attendant thereon, and incidentally a disconnected and incomplete record. As contradistinguished, my device is immediately complete since it records the total result of any number of movements. It is also less liable to err and moreover may be simplified to the extent of having its curve record traced on only one side of a given line.

The inventive conception is embodied in means which are hereinafter explained and variously combined in the claims, while the annexed drawing and particular description

thereof together set forth in detail one certain means constituting my invention, the disclosed means however, being but one of 55 various mechanical forms in which the principle of my invention may be applied.

Referring now to the drawing: Figure I is a diagrammatic representation of a device embodying my invention. Fig. II is 60 an enlarged detail. Fig. III is a section on line III—III of Fig. II.

As an aid to a clearer understanding, let the following be premised:

P=mean effective pressure—say 60 65 pounds.

L=length of stroke—say 3 feet.

A=area of piston in square inches—say 200 square inches.

N=number of strokes per minute—say 100.

$$\frac{\text{PLAN}}{33,000} = \text{H. P.}$$

or

$$\frac{60 \times 3 \times 200 \times 100}{33,000} = \text{H. P.}$$

75

Work=pressure $\times$ distance through which it travels.

1 horsepower (H. P.)=33,000 pounds $\times$ 80 1 foot per minute.

Instantaneous horsepower developed at any point by a piston traveling in a cylinder equals, instantaneous difference of pressure between the pressures on the two sides 85 of the piston at that point in pounds per square inch, multiplied by the area of the piston in square inches (a constant), multiplied by the instantaneous piston velocity in feet per minute, divided by thirty-three 90 thousand. Or

$$\text{Inst. H. P.} = \frac{\text{Inst. diff. of P} \times \text{A} \times \text{inst. vel.}}{33,000}$$

If therefore the pressure at one end of the 95 cylinder at any given moment, or when the piston is at any given point, can be instantly indicated with relation to the pressure at the other end and simultaneously the instantaneous velocity of such piston, it becomes possible to continuously ascertain the instantaneous differences of pressure on opposite sides of the piston and hence successively the instantaneous measures of 100

horse-power developed. I prefer to accomplish this desired end by the employment along with specific interconnecting mechanism, of the four main parts shown in the 5 drawing, viz: (1) A generator. (2) A rheostat. (3) A controller. (4) A recorder. These may be individually described as follows:

(1) A magneto, generator or any conceivable device for delivering electromotive force provided only that the latter (or in the case of the magneto chosen for representation in the drawing that the voltage) is at all times by suitable operative connection 10 directly proportioned to the velocity of the engine piston.

(2) A rheostat in which the E. M. F. is impressed into a permanent bank of resistance of approximately ten ohms value 15 and arranged or divided into any number of (say 30 or 40) equal steps. The end terminals of this rheostat are to be connected to a generator such as was tersely described in the paragraph just preceding. This connection may or may not include an additional calibrating resistance, as desired.

(3) The controllers (2 in number, by preference but not necessity) consist of duplicate face plates, carrying a number of contact 20 points (say 30 or 40) equally spaced and with corresponding points connected in multiple to successive steps of the form of rheostat mentioned in the paragraph next ahead of this. Each controller involves a 25 sliding contact whose position varies with the pressure on the corresponding end of the engine cylinder.

(4) The recorder consists of either an indicating, or a curve-drawing electric voltmeter showing results. This instrument is 30 to be connected to the sliding contact of the controllers and by means of a calibrating resistance may be made to read directly in horse-power upon a sheet properly graduated.

Proceeding next to an actual description of the drawing as illustrative of one combination of parts to which the broad principle of my invention may be applied; the cylinder of an engine has been designated by the 35 reference character A, the piston head as a' and the piston rod as a^2 . The cross-head a^3 articulates in the usual manner with the cross-head pin a^4 . A depending member a^5 is fixed to the cross-head a^3 and when moving 40 with it constitutes an actuating arm as will presently become apparent. The free end of this arm is provided with a fastening pin a^6 .

Seated in opposite ends of the cylinder A in any suitable way are a pair of pressure indicators B comprising the closed cylinders b' , inlet valves b^2 , plungers b^3 , calibrated 45 springs b^4 and outwardly projecting stems

b^5 . These stems b^5 have a link connection 50 each with an arm b^6 and so that each of the arms points in the general direction of the other. The link connections are effected through the agency of the links proper b^7 . Two additional links b^8 are however also 55 provided and these connect the rearward extremities of the arms b^6 with respective cylinders. This construction permits of a straight line motion on the part of the free extremities of the arms b^6 . These extremities are moreover fashioned with laterally projecting contact wipers b^9 , which are clearly shown in Figs. II and III. The arms b^6 are furthermore insulated immediately of their ends at b^{10} for the usual 60 purpose though to be hereinafter particularly stated. It is thus manifest that the free extremities of the arms b^6 carrying the wipers b^9 will rise and fall according as the pressure at the corresponding end of the 65 engine cylinder increases or diminishes. The contact wipers b^9 constitute one conjunctive agency of the controller mechanism the concluding description of which will 70 soon follow.

Located not far removed from the cylinder A is a magneto C which will be assumed to have a substantially constant field whether separately excited or of the permanent magnet type. The maximum voltage 75 to be delivered may vary between ten and fifteen volts. It comprises an armature c' which we will consider as rotating in the direction of the arrow, and two brushes c^2 . Two sheaves c^3 are pivotally mounted in 80 line with each other on opposite sides of the magneto C. Operatively stretched about these sheaves c^3 and upon the drum of the armature is a wire c^4 . This wire c^4 is secured to the pin a^6 and is therefore necessarily reciprocated upon the sheaves coincidentally with the reciprocation of the engine piston. The movement of the wire c^4 85 rotates the drum of the armature and in consequence delivers an E. M. F. which resembles a sine curve in value and changes 90 polarity at the end of each stroke of the engine. The voltage is while proportioned as the speed of travel of the engine piston.

Disposed between the controller arms b^6 is the rheostat D comprising the uniform resistance d' to the terminals d^2 of which the brushes c^2 are respectively connected by means of the connections d^3 and d^4 . This 95 resistance is designed to tend to cut the voltage down to zero. Flexible lead wires d^5 and d^6 , of any length suited to the available space, connect each with a step and extend respectively in opposite directions to a 100 pair of co-operative controller plates d^7 and d^8 , best seen in Figs. II and III. These plates are provided with a corresponding 105

- number of contact points d^9 and d^{10} with which one or the other of the two wiping points b^9 are adapted to contact thereby establishing the controller in its entirety.
- 5 The arrangement of the plates d^8 d^9 intermediately of the arms b^6 is such that sufficient sliding pressure is maintained therebetween. Inasmuch as the E. M. F. of the generating magneto is impressed on the 10 rheostat, and because this is of uniform resistance, an approximately uniform drop of potential with each step is produced. In the meantime, since the sliding wiping points on the arms b^6 are adapted to move 15 up and down over the points d^9 and d^{10} according to the pressure communicated from the cylinder, they span a drop of potential according to the effective pressure on the engine piston.
- 20 Located at any advantageous place is an electric voltmeter E. This is connected through the agency of wires e^1 and e^2 with the two arms b^6 . While the diagrammatic outline of the meter seen in the drawing is 25 assumed to be one of the direct indicating type, it may readily in a manner well known to the art, be converted or substituted so that a direct reading in horsepower may be had. This voltmeter or recorder as the case 30 may be measures the value of this last named difference of potential determined by the playing of the sliding contacts over the rheostat. This value of potential is found to be directly proportional to the 35 product of piston velocity and effective pressure on the engine piston. Hence, this value when multiplied by a constant, depending on the dimensions of the engine, establishes the results and when desired indicates the 40 horsepower. This will be found in agreement with the concluding equation appearing on page three.

My device lends itself admirably to the tests demanded in the rolling mill industry 45 where it is well to know the maximum instantaneous horse-power at any given minute. The fluctuations in generated horse-power during the successive rolling operations relative to that to be noted during the intervals may be immediately and continuously noted.

The application of my device upon locomotive or marine engines; steam driven machinery generally, including pumps and air 50 compressors; or indeed under any circumstances when a continuous record of the power generated might be desired, is likewise of pronounced practical utility.

On a reversing engine generally, the voltmeter is arranged with a zero-center scale 55 and deflects in either direction, according to the direction in which the engine is running.

In case my device is to be used in conjunction with an engine of two or more cyl-

inders, it becomes necessary to duplicate the 65 generator, rheostat and controllers and use a voltmeter with a double winding.

Heretofore devices which merely assisted toward the attainment of the results which my invention completes alone and for itself, 70 made it necessary subsequently to bring together the several preparatory data. Compound or duplex engines required that computations be figured from a plurality of separate charts. The tabulations derived in 75 accordance with my conception designate all the values—instantly, precisely and continuously summarized.

My invention being thus described with sufficient thoroughness, what I desire to secure by Letters Patent and therefore claim specifically, is:

1. In a device of the character described, the combination of an engine cylinder, a piston movable therein, pressure indicators 85 at opposite ends of said cylinder, a generator, mechanism operatively connecting said piston and generator, a rheostat, means operatively connecting said generator and rheostat and controller mechanism operatively connecting said indicators and rheostat and adapted to measure variations in potential for the purpose specified.

2. In a device of the character described, the combination of an engine cylinder, a piston movable therein, pressure indicators at 95 opposite ends of said cylinder, a generator, mechanism operatively connecting said piston and generator, a rheostat, means operatively connecting said generator and rheostat, a controller mechanism operatively connecting said indicators and rheostat, and an electric voltmeter operatively connected with said controller.

3. In a device of the character described, 105 the combination of an engine cylinder, a piston movable therein, pressure indicators at opposite ends of said cylinder, a generator, means operatively connecting said piston with the armature of said generator whereby 110 the movement of the former rotates the latter, an electrical measuring instrument including a divided bank of resistance, said instrument being operatively connected with said generator, and controller mechanism 115 adapted to connect different divisions of said resistance with said indicators for the purpose specified.

4. In a device of the character described, 120 the combination of an engine cylinder, a piston movable therein, pressure indicators at opposite ends of said cylinder and having arms, a magneto, means operatively connecting said piston with the armature of said magneto whereby the movement of the former rotates the latter, a rheostat having a plurality of equal steps disposed between said indicators, connections between the ter-

minals of said rheostat and the brushes of said magneto, duplicate controller mechanism movably connecting opposite leads from said rheostat with said indicator arms respectively, and a voltmeter operatively connected with said arms.

Signed by me, this 27th day of **January**, 1913.

WALTER H. HOLLSTEIN.
